COMPRESSOR UNIT OF A PULSATON SYSTEM

Bopp von Oberstadt, Berlin-Halensee, Germany,
assignor of one-half to Franz Liebhold, Berlin-
Halensee, GermanyApplication February 27, 1932, Serial No. 595,482
In Germany February 28, 1931

12 Claims. (Cl. 60—54.6)

My invention relates to a hydraulic brake apparatus destined for automobiles and comprising staged pistons, the piston having the smaller diameter being connected to the operating rod system and a yielding piston closing the annular space between the two piston stages. Both pistons travel conjointly along a course corresponding to the replenishing volume, whereupon the piston having the large diameter comes to rest and only the piston having the small diameter executes the course corresponding to the pressing volume. The improvement consists in a latch mechanism connecting both pistons only during their common replenishing course and being provided with an adjustable separating means, by which the connection between the two pistons is loosened shortly before the beginning of the pressing course, so that during the pressing course the moving smaller piston is separated from the stationary larger piston.

The adjustment of the moment of said separation allows to compensate from a single central place the play generated at all the braking places, that is to say at all the four wheels by the wear of the braking members. Following the wear of the braking members such compensation effects a pressing volume consonant with the original condition of the brake system before the wear and tear.

Prior braking systems are based on the principle that the quantity of the fluid filling the network of the conducting mains is enlarged. Such an enlargement is made unnecessary by the present purely mechanical adjustment apparatus, at least in the case that the original quantity of the fluid filling the conducting mains is preserved, that is to say that no losses have taken place. With other words: the plays generated by mechanical wear, and eventually small fluid losses too, are compensated by the present mechanical adjustment apparatus.

During the replenishing course the motion of the operating rod is transferred onto the annular piston having the large diameter by means of the latch mechanism. The sectional area of the inner piston having the small diameter is several times as great as the sectional area of the operating rod, with the result, that the pressure reacting onto the operating rod from said small piston may be larger and therefor the course described by the operating rod during the replenishment may be smaller than desired. Accordingly it is preferred to interpose a lever system becoming effective during the pressing course between the operating rod and the small piston.

The said lever system is arranged at right angles to the latch mechanism for the purpose to mount both on the same portion of the length of the brake applying system.

An embodiment of my invention is illustrated 5 in the annexed drawings in which

Figure 1 is a longitudinal sectional view showing the whole arrangement including the latch mechanism;

Figure 2 is a fragmental longitudinal sectional 10 view taken at right angles to the sectional view shown in Figure 1 and showing the lever system; and

Figure 3 is the front view of a detail.

Figure 4 is a longitudinal sectional view showing a section corresponding to Figure 1 on a larger scale and showing the parts in a position corresponding to that moment in which the brake shoes are brought to the wheels.

Fig. 5 is a longitudinal sectional view similar 20 to Fig. 2, the parts, however, being in operated position.

Referring now to the drawings, the master or compression cylinder *a* is provided with an outlet member *a*¹, with which a member *a*² for attaching the main pipe leading to the braking cylinders is connected. The annular piston *b* having a large diameter reciprocates within the master cylinder *a*. A cylindrical recess of the annular piston receives a portion of the interior 30 piston *c*. A collar *d* consisting of yieldable material is arranged between the cylinder *a* and interior piston *c* and provided with outer and inner flanges *d*₁ and *d*₂ tightening on the cylinder *a* and interior piston *c*. A weak spring *f* 35 being supported by the cylinder end wall *a*³ acts upon an annular sheet metal washer *e* laid into the collar *d* and tends to push the annular piston *b* in its extreme backward position. Said position is defined by a perforated 40 wall *g* abutting against the outer and inner flanges *j*₁ and *j*₂ of a collar *j* arranged at the inside of the cylinder cover *k*. The annular piston *b* has a long backward extending hub *b*₁ provided with a shoulder *b*₂ abutting against the wall *g* in the extreme backward position of the piston *b*.

A second weak spring *h* is interposed between the outlet member *a*¹ and the interior piston *c* provided at its front side with an annular groove *c*¹. The hole into which the member *a*¹ is 50 threaded, has a diameter sufficiently great that, after threading out the member *a*¹, the spring *h* and piston *c* may be removed at the front side and inserted again in the same way.

The inner portion *b*³ of the annular piston *b* 55

is provided with a hole or perforation b^4 for the purpose that the motion of the interior piston c relatively to the annular piston b is not prevented by air pressure.

5 A cylindrical housing m is screwed upon the backward portion of the cylinder a and may be adjusted and secured in its longitudinal position by screwing backward or forward.

The housing m is provided at its backward 10 end with a stepped portion m^1 and a narrower cylindrical projection m^2 extending backward. A bushing n abuts against the stepped portion m^1 and is provided with a cylindrical inner wall against which bears an annular operating member o . Said member is fixed upon an operating rod p having a thickened end portion p^1 extending into the bore c^3 of the long hub c^2 of the interior piston c . It is to be seen that the operating rod p is led on two places, that is to say, within the hub c^2 of the interior piston c by 15 means of the thickened portion p^1 and within the bushing n by means of the operating member o .

20 The thickened portion p^1 is provided with a longitudinal groove p^2 for the purpose that no air cushion is formed before the thickened portion p^1 of the rod p .

25 The hub b^1 of the annular piston b carries upon its backward end a plate q pressed or otherwise 30 fixed upon said hub and provided with two diametrically opposed pairs of ears q^1 . A driving latch member s is linked by means of a pivot r between the ears of each pair and provided with two sloping faces s^1 and s^2 joining together to 35 form a roof shape. The latch member s is always pulled inwardly by a spring t and abuts with its interior sloping face s^1 against a correspondingly sloping face o^1 of the operating member o , whereas a projecting edge o^2 of said member 40 prevents the latch member s from being swung inwardly above a desired limit.

45 During the first portion of the forward course of the operating rod p (the forward direction being from righthand to lefthand side in Figures 1 and 2) the latch member s abuts with an outer longitudinal face s^3 against the cylindrical inner face n^1 of the bushing n (Fig. 1). In this position the operating rod p together with the operating member o , the two opposed latch members s , the plate q , the hub b^1 of the annular piston b and said piston itself, and the interior piston c driven by the portion b^3 of the annular piston b , are driven together in the forward direction, so that both pistons move conjointly and 50 describe a large volume, thereby overcoming the small resistance existing during the replenishing course.

55 As soon as the edge s^4 , being the backward end of the latch member face s^3 has reached the front edge n^2 of the bushing n , the faces o^1 , s^1 , cooperating in the manner of sloping planes, urge the latch members s outward, thereby overcoming the resistance of the weak springs t . The sloping angle of the latch member face s^2 is the same as the sloping angle of the front face n^2 of the bushing n . In consequence thereof, the latch member s does not participate furthermore on the motion of the operating member o , but escapes into the recessed portion of the housing m , with the result, that all the parts being connected with the latch member s , especially the annular piston b , come to rest under the influence of the spring f , whereby the end position reached by the annular piston b is defined by the longitudinal position of the bushing face n^3 and therefor may

be adjusted by screwing the housing m along the cylinder a . But inasmuch as the driving member o is concerned, it moves unimpededly further, its cylindrical outer face o^3 sliding longitudinally along the inner edge faces s^5 of the latch members s , so that the latch members s remain disconnected for the duration of the pressing course.

5 A plate u is fixed upon the backward end of the hub c^2 of the interior piston c and abuts against a shoulder b^5 formed on said hub c^2 . This plate u is formed with two diametrically opposed arms u^1 Fig. 2, each being provided with a projection u^2 extending backward. The arms u^1 are arranged in a plane at right angles relative to the plane of the latch members s , as best shown in Figures 1 15 and 2. At either side of the plate u , the plate q is prolonged to form backward extending arms q^2 , upon each of which a bell crank lever w is mounted by means of a pivot v . Either lever is formed with a nose w^1 abutting against one of the projections u^2 . The backward end of each lever carries a roller x cooperating with a cam or key-shaped second operating member y fixed upon the operating rod p , abutting against a shoulder p^3 formed on the rod p and forming an abutment for the first operating member o , which is formed with two diametrically opposed recesses o^4 allowing the separation of the bell crank levers w , as best shown in Figures 2 and 3.

30 It is very important that the two lever arm lengths L^1 and L^2 (Fig. 2) of each bell crank lever w are unequal, so that a ratio differing from one to one exists between the exerted forces.

35 As long as the motion is transmitted through the latch members s in the manner specified above, the rollers x occupy their most inward positions shown in Figure 2, that is to say, the positions before the second operating member y . As soon as the latch members s are swung out and the pivot v of each bell crank lever w is come to 40 rest together with the annular piston b , whereas the operating rod p moves further, the second driving member y slides along under the rollers x and its cam or key-shaped faces pull outward the rollers x , so that the plate u is engaged at its 45 projections u^2 by the lever noses w^1 and driven forward. This motion is transmitted through the hub c^2 to the interior piston c , so that the interior piston only describes the pressing course, but moves thereby with a smaller velocity than the operating rod p . The ratio of the velocities depends upon the ratio of the lever arms L^1 to L^2 , and furthermore upon the cam face of the second operating member y . Inasmuch this cam 50 face may be chosen conveniently, the ratio of the velocities may be adapted to the increasing pressure of the brake members.

55 If the driver finds, that owing to wear in the lining or leather of the brake bands or shoes, an effective braking cannot be accomplished, the operating rod p being in its end position, he has only to adjust the housing m by screwing it over the cylinder a to a length corresponding to amount of wear. The hydraulic brake mechanism will then operate again with the initial correct efficiency.

60 All the parts are returned by motions in the reverse direction and reverse sequence. Thereby it is important that the spring h effects a positive engagement between the rollers x and the second driving member y and that the springs t swing 65 inward the latch members s , as soon as the operating member o transgresses with its edge o^1 the latch member edges s^4 in its return motion.

What I claim is:—

1. In a hydraulic control unit, the combination of a cylinder, a housing on said cylinder, an annular piston provided with an elongated hub 5 in said cylinder, an interior piston provided with an elongated hub in said annular piston, said hub of both pistons extending into said housing, a rod extending through said housing and also extending at its inner end into the hub of said interior piston, latch means connected within the housing to said hub of the annular piston, lever actuated means connected to the hub of said interior piston within said housing, means carried by said rod for first operating upon said latch 10 means for synchronously moving said pistons inwardly within said cylinder, and means on said rod for operating said lever means for further moving said interior piston within said cylinder after movement of said annular piston has terminated.
2. In a hydraulic control unit, the combination of a cylinder, a housing on said cylinder, an annular piston provided with an elongated hub in said cylinder, an interior piston provided with an elongated hub in said annular piston, said hubs of both pistons extending into said housing, a plate provided with ears fastened to the outer end of said hub of the annular piston, said plate also provided with outwardly extending arms, bell crank levers pivotally mounted on said arms, spring pressed latch members pivotally mounted on said ears, a rod extending at its inner end into the hub of said interior piston, a plate provided with arms fastened to the outer end of the hub of the interior piston, said bell crank levers adapted to operate upon said ears and adapted to be operated upon by said operating member for forcing both pistons towards the inner end of said cylinder, and cam means fastened to said rod and adapted to operate upon said bell crank levers for causing said levers to press upon the arms of said plate for further moving the interior piston within said cylinder after the annular piston is at rest, substantially as shown and described.
3. In a hydraulic control unit, the combination of a cylinder, a housing adjustably mounted on said cylinder, an apertured wall in said cylinder, a flanged packing in said cylinder disposed against said wall, a cover in the outer end of said cylinder against said packing, an annular and an interior piston in said cylinder between said wall and the inner end of the cylinder, means in said housing and connected to both pistons for moving the same synchronously towards the inner end of said cylinder, and means in said housing and connected to said interior piston for imparting further movement thereto while the annular piston is stationary.
4. In a hydraulic control unit, the combination of a cylinder, a housing adjustably mounted on said cylinder, a pair of pistons in said cylinder and provided with hubs extending into said housing, latch members provided with means connecting the same to one of the hubs within said housing, lever means provided with means operably connecting the same to the hub of the other piston within said housing, operating means in said housing and first operating on said latch members for imparting synchronous movement to said pistons, and operating means in said housing for imparting movement to said lever means for operating the hub and its piston carrying said lever means after movement of the latch members has ceased.
5. In a hydraulic control unit, the combination of a cylinder, a housing on said cylinder, an annular piston provided with an elongated hub in said cylinder, an interior piston provided with an elongated hub in said annular piston, said hubs of both pistons extending into said housing, a plate provided with ears fastened to the outer end of said hub of the annular piston, said plate also provided with outwardly extending arms, spring pressed latch members pivotally mounted on the outer ends of said ears, bell crank levers pivotally mounted on the outer ends of said arms, a plate provided with arms fixedly secured to the outer end of the hub of the interior piston, said plate positioned between said first mentioned arms, said bell crank levers adapted to operate 10 on the arms of said plate fastened to the hub of the interior piston, a rod provided with an enlarged inner end, said inner end provided with a longitudinally extending groove, said grooved inner end securely fastened within the hub of 15 the interior piston, an annular operating member fixedly secured to said rod within the outer end of said housing and adapted to operate upon the outer ends of said latch members for pushing inwardly upon said latch members and subsequently moving against their inner edges, and a cam fastened to said rod within said operating member and adapted to operate upon said bell crank levers for causing the same to bear against the arms of the plate carried by the hub of the 20 interior piston, for forcing the interior piston further inward after movement of the annular piston has terminated, substantially as shown and described.
6. In a hydraulic control unit, the combination of a cylinder, a housing adjustably mounted on said cylinder, a pair of pistons, one within the other, positioned in said cylinder, said pistons provided with hubs extending into said housing, means in said housing and operating 25 upon the hub of one of the pistons for moving the same inwardly, means in said housing and operating upon the hub of the other piston for giving this last mentioned piston a further movement within said cylinder, and means associated 30 with said operating means for adjusting the stroke of movement of the operating means by adjusting the housing upon said cylinder.
7. In a hydraulic control unit, the combination of a cylinder, a housing provided with an open outer end mounted upon said cylinder, a bushing in the open end of said housing, said bushing provided with a bevelled latch member engaging face, a pair of pistons in said cylinder and provided with nested hubs, said hubs extending 35 into said housing, latch members provided with means connecting the same to one of said hubs, said latch members adapted to engage said bevelled latch member engaging face on said bushing, a rod extending into the hub of one of said pistons, an operating member fastened to said rod within said bushing, said operating member provided with a bevelled face engaged by said latch members during the initial stroke prior to the latch members being forced into engagement with said bevelled face of said bushing, and said rod provided with means connecting the same to one of said hubs for imparting further movement to this last hub and its piston in- 40
- 50
- 55
- 60
- 65
- 70
- 75

dependent of the hub to which said latch members are connected.

8. In a hydraulic control unit, the combination of a cylinder, a housing adjustably mounted on said cylinder, a pair of nested pistons in said cylinder, latch means in said housing and connected to one of the pistons for moving both pistons synchronously together within said cylinder, and lever means in said housing and connected to the other piston for imparting further movement thereto.

9. In a hydraulic control unit, the combination of a cylinder, a pair of nested pistons operating in said cylinder, means for moving said pistons to displace the liquid in the head of the cylinder, a housing adjustably mounted on said cylinder, positive locking means mounted in said housing for locking one of said pistons against return movement when under pressure of the liquid in the head and during the continued movement forward by the other piston.

10. In a hydraulic control unit, the combination of a cylinder, a pair of nested pistons operating in said cylinder, means for moving said pistons to displace the liquid in the head of the cylinder, latch means connected to one of the pistons for moving both pistons synchronously together within said cylinder, lever means connected to the other piston for imparting further movement of the latter, a housing adjustably mounted on said cylinder, positive locking means mounted on said housing cooperating with said latch means for locking one of said pistons against return movement when under pressure of the liquid in the head and during the continued movement forward by the other piston.

11. In a hydraulic control unit, the combination of a cylinder, an annular and an interior piston operating in said cylinder, means for operating upon said annular piston for synchronously moving both pistons, means for operating only upon said interior piston to displace the liquid in the head, a housing adjustably mounted on said cylinder, positive locking means mounted in said housing for locking said annular piston against return movement when under pressure of the liquid in the head and during the continued movement forward by the interior piston.

12. In a hydraulic control unit, the combination of a cylinder, an annular piston provided with an elongated hub in said cylinder, an interior piston provided with an elongated hub in said annular piston, said interior piston extending a distance into the hub of said annular piston and with its hub projecting a distance beyond the outer end of the hub of said annular piston, means for moving said pistons to displace the liquid in the head of the cylinder, a housing adjustably mounted on said cylinder, said both hubs extending into said housing, means in said housing operating on the hub of said annular piston for synchronously moving said pistons inwardly within said cylinder, means in said housing operating on the hub of said interior piston for further advancing the latter, positive locking means mounted in said housing for locking the annular piston against return movement when under pressure of the liquid in the head and during the continued movement forward by the interior piston.

BOPP VON OBERSTADT.
